UNITED STATES PATENT OFFICE.

GUSTAVUS A. WIKANDER, OF PORTLAND, OREGON.

ESCAPEMENT MECHANISM FOR TYPE-WRITERS.

1,261,880.

Specification of Letters Patent. Patented Apr. 9, 1918.

Application filed November 9, 1916. Serial No. 130,463.

To all whom it may concern:

Be it known that I, GUSTAVUS A. WIKANDER, a citizen of the United States, and a resident of Portland, Multnomah county,

5 State of Oregon, have invented a certain new and useful Improvement in Escape-
ment Mechanism for Type-Writers, of which the following is a specification.

This invention relates generally to type-
10 writers and its purpose is to provide an im-
proved escapement mechanism by means of
which the typewriter will be made capable
of operation at a higher rate of speed and
with less manual effort on the part of the
15 operator.

Prior types of escapement mechanisms de-
pend for their reaction upon the contraction
of a spring placed under tension by the de-
pression of a key. However, each time a
20 key is depressed, the resisting action of said
escapement spring imposes a labor upon the
operator slight in itself, but summatively
large. Furthermore, the action of the es-
capement mechanism spring is not entirely
25 satisfactory, because it does not permit a
fast operator to work at highest speed.
Speed in typewriting depends on the reac-
tion or return of the escapement mechanism.

The main objects of my invention are: to
30 provide a typewriter escapement mecha-
nism the return movement of which is not
dependent upon the reaction of a stressed
spring; also to provide improved means for
operating the return movement of this es-
35 capement mechanism by which the work of
such operation will be imposed upon a source
of power, such as electric energy. A fur-
ther object of my invention is to combine
the working elements of my improved
40 mechanism in an apparatus adapted for at-
tachment to a typewriter of standard make.

The accompanying drawing illustrates the
general construction and operation of my de-
vice as applied to an Underwood typewriter.

45 The typewriter itself is illustrated in
fragmental form, only such parts being
shown as will define the location and action
of the devices which are comprised in my
invention. *a*, *b* and *c* are parallel base mem-
50 bers of the typewriter frame, *d* is the platen
roll, *e* the carriage, *f* the carriage guide rod,
g is the tape which connects the spring with
the carriage, and *h* the carriage pinion rack.
i is a finger key lever pivoted at *j*; *k* is a
55 bell-crank pivoted at *m*, and *n* is a type-bar
pivoted on the bearing rod *o* in the rigid

segment *p*. The bell crank *k* forms the con-
necting element between the key-lever *i* and
type-bar *n*, so that when the key-lever is de-
pressed, the type-bar will be operated, as 60
shown in the broken lines of the drawing.

A bracket *q* is mounted on the typewriter
frame members *a* and *c*, and said bracket
is provided with parallel pivot shafts *r*, *s*.
A shaft *t*, perpendicular to the shafts, *r*, *s*, 65
is supported at the upper end of the bracket
q, and the escapement ratchet *u* and pinion
v are mounted on said shaft, the carriage
rack *h* being engaged with the pinion *v*. A
lever element *6* is pivotally mounted on the 70
shaft *r*, said lever element being provided
at one end with a slot adapted to engage a
pin *7*, of a lever arm *8*, the latter being fixed
on a shaft *9*. The latter element has no
bearing on my invention and is merely shown 75
because of its presence as an integral part
of the typewriter illustrated.

The pivoted pawls *w* and *x* are the pallets
of the escapement mechanism, and their
movement permits the spacing mechanism to 80
act. The pawl operating frame *y* is hori-
zontally movable, it is connected at its rear
end to the pawl *x* and is provided with arms
10 which are pivoted to the upper end of
the rock lever *6*. 85

At the front of the frame *y* is a guide
member *z* slidable in a slot of the segment *p*.
The frame *y* is provided with a member *2*,
known as a universal bar, adapted to be
struck by a shoulder *3* on the type bar *n* just 90
before the latter reaches the position shown
in the broken lines of the drawing. The
consequent movement of the frame *y* to the
position shown in the broken lines of the
drawing will rock the pawl *w* out of engage- 95
ment with the ratchet *u*, and the pawl *x*
into engagement with the same. Said move-
ment will also rock the member *6*, through
the arms *10*, as obvious. Then, upon the re-
turn of the frame *y* to initial position, the 100
escapement device will permit the pawls to
operate so as to permit the ratchet to rotate
one tooth, and thus space the carriage a cor-
responding distance. The frame *y* is pro-
vided with a stud *4*. A fixed arm *5* projects 105
from the bracket *q*. Ordinarily a tension
coil spring (not shown) connects the stud *4*
and arm *5*, so that when the type bar throws
the frame *y* backward, the spring will be
stressed, and the reaction of said spring will 110
tend to return the parts to initial position,
as above described. However, the stressing

of the spring each time a type-bar is operated offers a certain resistance which must be overcome by manual effort of the operator. The device of my invention has for its 5 purpose to eliminate said spring entirely, and to substitute therefor an outside source of energy for doing the work ordinarily done by said spring. To this end I mount a bracket 11 on the rear of the typewriter. 10 Supported on the bracket is an electro magnet 12. An armature 13 is pivoted on a shaft 14, and said armature is mounted on one arm of a pump handle lever 15, the other extremity of which lever is pivotally connected to the upper end of the lever 6 by a link 16. A bracket 17 supports an adjustable screw 18, which forms one member of an electric switch. A resilient arm 19 forms the other member of said switch. A finger 20, on 15 the lever 15, is adapted to bear against the resilient arm 19 whenever said lever 15 is rocked, and thus cause said switch members 18 and 19 to contact and close the magnet circuit, of which 21 and 22 are the conductors and 23 is a battery, or other source of electric energy.

The general operation of my device is as follows:

Normally the parts are in the positions 30 shown in the full lines of the drawing. Whenever a key is depressed the type-bar n will be actuated as shown. However, instead of the escapement mechanism spring being stressed, as would be the case with 35 ordinary types of such mechanism, there will be no resistance offered to the action except that of rocking the armature 13, and this rocking movement is so slight and the leverage so compounded that such resistance is negligible. As the armature is rocked, the 40 switch member 19 will be moved so as to close the magnet circuit, whereupon the magnet will be energized, attracting the armature and causing said parts to be returned 45 to initial position, and in so doing opening the electric switch. The action of the magnet is much more positive, quicker and energetic than that of the spring it replaces, and the result is, that in addition to relieving 50 the operator of the work of operating the escapement mechanism, the type-bar and other parts will be kicked back into initial position much quicker, the spacing mechanism will work faster, and the general operation of the machine made faster and easier.

Copies of this patent may be obtained for five cents each, by addressing the "Commissioner of Patents
Washington, D. C."

I claim:

1. In a typewriter escapement mechanism, the combination with the pallets of said mechanism and key-controlled means operating said pallets in one direction, of an 60 electromagnet element and means operated thereby moving said pallets in the opposite direction, and a switch in the circuit of the electromagnet closed by the depression of a key and opened by the consequent movement 65 of the armature of said magnet.

2. In a typewriter spacing mechanism, the combination of a ratchet wheel, a pivoted member carrying pallets adapted to alternately engage such ratchet wheel, key-actuated type bars, means operated by the latter for moving said pivoted member in one direction, an electromagnet element, means actuated thereby for moving said pivoted member in the opposite direction, and a 70 switch in the circuit of the electromagnet closed by the depression of a key and opened by the consequent movement of the armature of said magnet.

3. In a typewriter spacing mechanism, the combination of a ratchet wheel, a pivoted member carrying pallets adapted to alternately engage such ratchet wheel, key-actuated type bars, means operated by the latter for moving said pivoted member, an 80 electromagnet, a pivoted armature therefor provided with a projecting arm, a connection between this arm and said pivoted member, a make-and-break in the circuit of said magnet operated by the movement of said arm of 90 the armature, whereby the movement of said arm in one direction closes said circuit, and the reverse movement of said arm, due to the energizing of said magnet, breaks said circuit again. 95

4. In a typewriter escapement mechanism the combination with the pallet element of said mechanism and key-controlled mechanism operating such pallet element in one direction, of an electromagnet element and 100 means operated thereby for operating said pallet element in the opposite direction, and a switch in the circuit of the electromagnet closed in time with the actuation of a type bar of the typewriter and opened in time 105 with the movement of the armature of said magnet when the circuit of the latter is closed.

G. A. WIKANDER.
